CLAIM

The ornamental design for a glitter decorated container, as shown and described.

DESCRIPTION

FIG. 1 is a front perspective view of the glitter decorated container of the instant invention;

FIG. 2 is a side elevational view thereof;

FIG. 3 is a top view thereof;

FIG. 4 is a bottom view thereof; and,

FIG. 5 is an opened exploded side elevational view thereof. The broken lines shown are included for the purpose of illustrating the unclaimed portions of the article and form no part of the claimed design.
